IGNITION SYSTEM.

Application filed April 2, 1923. Serial No. 629,398.

The present invention relates to improvements in ignition devices and more particularly to that type of ignition devices included in ignition systems for internal combustion or explosion engines, which systems include mechanism for interrupting circuits to provide sparking impulses.

It is among the objects of the present invention to provide an ignition device where-
10 in the breaker mechanism is kept substantially free from disintegration deposits due to sparking, thereby providing clean contacting surfaces in the breaker and facilitating current passage therethrough.

15 Further objects and advantages of the present invention will be apparent from the following description, reference being had to the accompanying drawings, wherein preferred forms of the embodiments of the invention are clearly shown.

In the drawings:

Fig. 1 is a plan view of the ignition unit; the circuit interrupter contacts being shown in engaged position.

25 Fig. 2 is an enlarged view similar to Fig. 1, the various elements of the device being shown in a position where the movable contact has been moved, relative to the stationary contact without disengaging the two.

20 Fig. 3 is a view similar to Fig. 2 showing the various elements in the position when the contacts have been separated.

Fig. 4 is a side view of the movable elements of the interrupter device.

35 Fig. 5 is a view similar to Fig. 4 taken from the opposite side of the interrupter device.

40 Fig. 6 is a diagrammatic view showing the electrical connections of a system in which this ignition device is used.

A preferred manner of carrying out the objects of the present invention is to mount one of the contacts of the timer on a pivoted arm and to provide means actuated by a power driven device, such as a timer cam, for moving the fulcrum of the lever so as to slide the movable contact relative to the stationary contact, and then separating the contacts. Consequently the contacts after being engaged again will slide, the one relatively to the other.

Referring to the drawings, the ignition device is shown comprising a pair of co-operating contacts including a movable one, designated by the numeral 20 and a stationary one designated by the numeral 21. The latter is adjustably supported on a bracket 22, which is mounted in but insulated from the timer cup 23.

The lever carrying one of the contacts, termed the movable contact 20, is designated by the numeral 24. The end of the lever, opposite the contact element 20, is provided with a circular portion 25 which encompasses a bushing 26 adapted to form a bearing for the mounting or fulcrum pin 27 of said lever.

The means for moving the fulcrum 27 of the lever 24 before the contacts 20 and 21 are separated, includes an operating arm 28, having its one end pivoted on a stud 29 carried in the timer cup 23, while the other end of said arm is provided with a rubbing block 30 in operative connection with the driving element or cam 31.

An ear portion 32 is formed in the main body of the operating arm 28 between its pivotal point 29 and the rubbing block 30. The fulcrum pin 27 which rotatably carries the lever 24 is supported by this ear portion 32 and the operating arm 28. A spring 33 having its one end secured to the terminal post 34 passes around the pivotal point of the arm 28 and has its opposite end anchored to the contact lever 24.

This spring tends to hold the contact element 20 in engagement with the stationary contact 21 while at the same time pressure is exerted upon the lever 24 which as has been mentioned heretofore, is mounted on and carried by the arm 28, thus this pressure upon the lever 24 will be transmitted to the operating arm 28 to cause said arm or rather its rubbing block 30 to be held in operative connection with the driving element or cam 31.

Assuming that the various elements of this device are in a position as is shown in Fig. 1, where the rubbing block 30 is shown riding on the flat surface of the cam element 31 nearest to its axis, and the contact element 20 being in aligned position and in engagement with the stationary contact 21, it will

be seen that no portion of the arm 28 nor the end of the rubbing block opposite to that engaging with the cam is in engagement with the lever 24 excepting of course the fulcrum pin 27 of said lever which as has been mentioned heretofore, rotatively supports the arm 24.

Now assuming that the ignition device has been operated to cause rotation of the cam 31 in a clockwise direction, to a position as is shown in Fig. 2, it may be clearly seen that the rubbing block 30 has moved along the surface of the cam 31, approaching its highest point on said cam but not yet reaching same thus having rotated the lever 28 about its fulcrum point 29 in a counter-clockwise direction. This rotation of the arm 28 has also rotated the fulcrum point 27 of the lever 24 radially relative to the fulcrum point 29 of the lever 28. The end of the rubbing block 30 opposite to that engaging with the cam 31 has now also been brought into engagement with the arm 24. The action of the spring is to hold the contact element 20 in engagement with the stationary contact element 21 and no force having been brought into effect to push or operate the arm 28 to move the contact 20 out of engagement with its cooperating contact 21, the aforementioned rotation of the pivoted point 27 of arm 24 radially to the pivot point 29 of arm 28 has therefore caused a sliding movement of the contact element 20 relative to the contact element 21 without disengaging the same, moving the contact 20 out of alignment with this contact element 21 as is shown in the Fig. 2. This rubbing movement between the two contact elements creates friction therebetween which tends to keep the faces of said contact elements polished thus eliminating disintegration deposits on the faces thereof.

Upon further movement of the cam element 31 to cause the rubbing block 30 to ride upon the highest point of the cam as is shown in Fig. 3, the end of the rubbing block 30 engaging with the contact arm 24 will rotate the contact arm 24 with the arm 28 as a unit around the pivot point 29, thus moving the contact point 20 out of engagement with the stationary contact element 21.

It will be seen that when the rubbing block 30 again rides off the highest point of the cam 31, the contact element 20 will first be moved to engage with the stationary contact element as is shown in the Fig 2 and further rotation of the cam 31 will cause the contact element 20 to be moved on the contact element 21 with a sliding motion into aligned position as is shown in the Fig. 1.

In the Fig. 6, there is shown a circuit connection of a system in which an ignition device of this type is used. The movable contact element 20 is shown connected to one end of the primary winding 40 of an ignition coil while the stationary contact 21 is shown connected to one side of a storage battery 41. The one side of the storage battery is connected to the opposite end of the primary winding 40, through a switch 42.

Current flowing through the primary circuit including the primary coil 40 and the contacts 20 and 21 being intermittently broken by these contacts will tend to cause an arcing which causes the surfaces of the contact points to become pitted thereby tending to affect the passing of current across these points. By the use of the present invention, this pitting of the contact surfaces or rather accumulation of contact disintegration material upon their surfaces will be substantially eliminated inasmuch as the contacts previous to being broken and immediately after again brought together will be slid one on the other thereby tending to rub off any such accumulation as might take place and facilitating the passing of current therethrough.

While the form of embodiment of this invention as herein disclosed, constitutes a preferred form, it is to be understood that other forms might be adopted, all coming within the scope of the claim which follows.

What we claim is as follows:

In an ignition device for internal combustion engines and in combination with an engine driven cam, an operating arm, one end of which is pivotally supported from a fixed support; a rubbing block carried by the free end of said arm, and which is adapted to engage the cam aforesaid; a contact carrying lever overlying and extending beyond the extremity of said operating arm, and which lever is pivotally connected with said operating arm at a point offset from a line joining the pivotal support of said arm and the extremity of said rubbing block which engages said cam; a fixed contact; and a movable contact carried by the free end of said contact carrying lever and adapted to engage said fixed contact; said rubbing block being arranged substantially at right angles to said operating arm, and the end thereof remote from said cam being adapted to engage said contact carrying lever to separate said contacts.

In testimony whereof we hereto affix our signatures.

JOHN T. FITZSIMMONS.
HUGH WALLACE.
